[57] CLAIM

The ornamental design for a wall-mountable tape dispenser or the like, as shown and described.

DESCRIPTION

FIG. 1 is a perspective view of a wall-mountable tape dispenser or the like showing my new design;

FIG. 2 is a rear elevational view on a reduced scale;

FIG. 3 is a left side elevational view of FIG. 2; and

FIG. 4 is a top plan view of FIG. 2.
